M. A. GARRITY

DOOR STOP AND CATCH

Filed Sept. 8, 1923

Inventor
M. A. Garrity.

By *A. Randolph Jr.*
Attorney

UNITED STATES PATENT OFFICE.

MARTIN A. GARRITY, OF PHILADELPHIA, PENNSYLVANIA.

DOOR STOP AND CATCH.

Application filed September 8, 1923. Serial No. 661,597.

To all whom it may concern:

Be it known that I, MARTIN A. GARRITY, a citizen of the United States, residing at Philadelphia, in the county of Philadelphia 5 and State of Pennsylvania, have invented certain new and useful Improvements in Door Stops and Catches; and I do hereby declare the following to be a full, clear, and exact description of the invention, such as 10 will enable others skilled in the art to which it appertains to make and use the same.

The present invention has for its object the provision of a device whereby to prevent injury to a wall by impact of a door knob 15 or key therewith when the door is swung open and to engage and hold the door in open position and prevent its closing by a draft of air or a slight knock or jolt thereagainst.

Other objects and advantages will be apparent and suggest themselves as the nature 20 of the invention is understood.

While the drawings illustrate an embodiment of the invention it is to be understood 25 that in adapting the same to meet different conditions and requirements, various changes in the form, proportion and minor details of construction may be resorted to without departing from the nature of the invention.

Referring to the accompanying drawings 30 forming a part of the application:

Figure 1 is a top plan view of the device, the parts being separated,

Figure 2 is a central, longitudinal section 35 thereof,

Figure 3 is a side view partly in section with the members partly engaged,

Figure 4 is a view similar to Figure 3, the members being in full engagement, and

Figure 5 is a detail view in perspective of 40 the locking dog.

Corresponding and like parts are referred to in the following description and designated in the several views of the drawings 45 by like reference characters.

The device comprises complementary members 1 and 2, each having a base plate whereby it may be attached to the door and sub-base or like part, as required. The member 50 1 is in the nature of a plunger and is provided in its outer end with a slot 3 in which is located a dog 4 mounted upon a pivot 5. The inner or tail end of the dog 4 is oppositely tapered and its outer end is offset and terminates in a forwardly disposed beak 6. The offset portion 7 of the dog is adapted

to project laterally beyond a side of the member 1 to engage a stop shoulder of the member 2 and lock the two members and hold the door in open position. 60

The member 2 consists of a cylinder or barrel having its outer portion constricted to snugly receive the member 1 and to provide an inner annular shoulder 8 to engage the laterally projecting offset portion 7 of 65 the dog 4. A pressure plug 9 slidably mounted within the member 2, has its outer or forward end beveled, as indicated at 10, and its inner or rear end recessed to receive one end of a helical spring 11 disposed 70 within the member 2 and held in place by means of a pin 12. The helical spring 11 normally exerts a pressure to urge the plug 9 forwardly, whereby to yieldably engage the offset portion 7 of the dog 4 and hold the 75 projecting end thereof in engagement with the stop shoulder 8. The beak 6 of the dog 4 engages the beveled portion 10 of the pressure plug 9 and is adapted to ride thereon when a sufficient force is exerted to withdraw the member 1 from the member 2. In this case, the dog 4 turns upon the pivot 5 and the plunger 9 is pressed inwardly against the tension of the spring 11 until the projecting portion of the dog clears the 85 shoulder 8, when the door may be closed.

In practice, either one of the members may be attached to the door and the other to the subbase or wall, the parts being so arranged that upon opening the door, the 90 member 1 enters the member 2. The spring pressed plunger 9 acts as a buffer to minimize the impact and also operates to hold the dog 4 with its laterally projecting end in engagement with the stop shoulder 8. To 95 close the door, sufficient force must be exerted to withdraw the member 1 from the member 2 and this can be effected only by a riding of the beak 6 upon the beveled end 10 of the plunger 9. It will thus be understood that a draft of air or a slight knock against the door will not operate to close the same.

What is claimed is:

1. A combined door stop and catch comprising complementary members, the one consisting of a barrel and the other a plunger, a dog carried by the plunger and adapted to engage a fixed shoulder within the said barrel, and a spring pressed plunger within 105 the barrel arranged to engage said dog and operating as a buffer and also acting to nor- 110

2 mally hold the said dog in engagement with the stop shoulder of the barrel.

2. A combined door stop and catch comprising a barrel having an inner stop shoulder, a plunger, a dog carried by the plunger and adapted to engage the stop shoulder of the barrel, and a spring pressed plunger within the barrel and adapted to cooperate with the said dog and plunger and having a 10 beveled portion for the projecting end of the dog to ride upon.

3. A device of the character specified comprising a barrel having an inner annular shoulder, a spring actuated plunger within 15 the barrel having its forward end beveled, a plunger adapted to enter the barrel, and a dog pivoted to the plunger to one side of a central line and having a laterally disposed offset portion adapted to engage the annular shoulder of the barrel and terminating 20 in a forwardly disposed beak adapted to en-

gage and ride upon the beveled end of the spring pressed plunger.

4. A combined door stop and catch comprising a barrel having an inner annular 25 shoulder, a spring actuated plunger within the barrel having its forward end beveled, a slotted plunger adapted to enter the barrel, and a dog pivoted within the slot of the plunger and comprising a tapered tail end, a 30 laterally offset portion and a forwardly disposed beak, the latter adapted to engage and ride upon the beveled end of the spring actuated plunger and the projecting part of the laterally offset portion adapted to engage 35 the inner annular shoulder of the barrel.

In testimony whereof I affix my signature in presence of two witnesses.

MARTIN A. GARRITY.

Witnesses:

FRED Z. MEYER,

FRANK BEISLER.
